NECKTIE

Collingwood Teddy Tinling, London, England, assignor to Tinling, Inc., New York, N. Y., a corporation of New York

Application November 6, 1951, Serial No. 17,297

Term of patent 3½ years

(Cl. D3—16)

To all whom it may concern:

Be it known that I, Collingwood Teddy Tinling, a subject of the King of Great Britain, residing at London, England, have invented a new, original, and ornamental Design for a Necktie, of which the following is a specification, reference being had to the accompanying drawing, forming part thereof.

In the drawing:

The single figure is a front elevational view of a necktie embodying my new design.

The undisclosed portions of the necktie are unornamented and of conventional configuration.

I claim:

The ornamental design for a necktie, substantially as shown and described.

COLLINGWOOD TEDDY TINLING.
